[57] **CLAIM**

The ornamental design for a housing for electronic equipment used in data communication, as shown and described.

DESCRIPTION

FIG. 1 is a top, front, right side perspective view of a housing for electronic equipment used in data communication showing my new design;

FIG. 2 is a top, rear, left side perspective view thereof;

FIG. 3 is a bottom, front, right side perspective view thereof;

FIG. 4 is a right side elevational view thereof. Stippling is used in FIGS. 1-3 in order to indicate contrast.

FIG. 1

FIG. 2

FIG. 3

FIG. 4
